UNITED STATES PATENT OFFICE.

GEORGE SNYDER, OF INDIANAPOLIS, INDIANA, ASSIGNOR TO GEORGE E. KRAUSE, OF SAME PLACE.

FOLDING OR BED LOUNGE.

SPECIFICATION forming part of Letters Patent No. 236,727, dated January 18, 1881.

Application filed March 18, 1880. (No model.)

To all whom it may concern:

Be it known that I, GEORGE SNYDER, of the city of Indianapolis, county of Marion, and State of Indiana, have invented certain new and useful Improvements in Folding or Bed Lounges, of which the following is a specification.

The object of my invention is to provide the folding part of an ordinary bed-lounge with a set of strong serviceable feet for supporting the same when the lounge is open, and to provide the permanent part with a suitable slot or opening to receive said feet when the lounge is closed, which is accomplished as hereinafter more particularly set forth.

Referring to the drawings, which are made a part hereof, Figure 1 is a top or plan view of the frame of my improved bed-lounge when open. Fig. 2 is a front elevation thereof, showing by means of dotted lines the position of the parts when closed; Fig. 3, an elevation of the lower end, and Fig. 4 a transverse vertical section of the closed lounge on the dotted line *xx*.

In said drawings, the portions marked A represent the frame-work or rigid portions of the main part; B, the similar portions of the folding part, which is hinged to the main part in any ordinary or approved manner; C, hinges connecting the two said parts together; D, two feet, preferably connected together by a bar, E, and hinged to the front rail of the folding part, in the manner shown; F, hinges connecting the feet to said rail; G, a hasp or button for fastening the feet D to the frame-work B, and H a slot or opening in the frame A.

As before indicated, my invention principally consists in so attaching feet to the folding part of a bed-lounge that, while they serve the purpose of supporting it when the lounge is open, they shall be received into a recess or opening in the permanent part so as to be out of sight when the lounge is closed. To this end the hinges F are so attached to the feet D

and frame-work B that said feet may swing from a vertically-downward position, as when in use, to an upright position, as when the lounge is about to be closed, or about one hundred and eighty degrees. An opening, H, is formed in the main part of the lounge, near to its back, through which the feet D descend in closing the lounge, as shown in Fig. 4, and thus this object of my invention is attained. The slot H also serves to receive the edges of the bed-clothing when the lounge is in use as a bed, and thus one very common inconvenience of bed-lounges is avoided.

There may be one or more of the fastening devices G, and they may be variously attached, the only purpose being to secure the feet D rigidly in position when the lounge is open.

By reason of the secure manner of attaching the feet D, which renders them rigid when in use, and their adaptability to be inclosed out of sight when the lounge is closed up, casters D' may be applied thereto, thus enabling the lounge to be easily moved about when it is open, as well as when it is closed.

Having thus fully described my said invention, what I claim as new, and desire to secure by Letters Patent, is—

In a bed-lounge, the combination of a permanent part provided with a slot or opening, H, and a folding part hinged to said permanent part, and having supporting-feet hinged thereto, said slot being for the purpose of receiving the feet of the folding part when the lounge is closed and the edges of the bed-clothing when it is open, substantially as set forth.

In witness whereof I have hereunto set my hand and seal at Indianapolis, Indiana, this 15th day of March, A. D. 1880.

GEORGE SNYDER. [L. S.]
